UNITED STATES PATENT OFFICE.

CLARENCE T. ROGERS, OF NEW YORK, N. Y.

DOOR-CHECK.

1,090,879.

Specification of Letters Patent. Patented Mar. 24, 1914.

Application filed May 28, 1913. Serial No. 770,526.

To all whom it may concern:

Be it known that I, CLARENCE T. ROGERS, of the city, county, and State of New York, have invented a new and useful Improvement in Door-Checks, of which the following is a full, clear, and exact description.

My invention relates to improvements in door checks, and the object of my invention is to produce a very simple and efficient form of door check which can be conveniently attached to a door and frame in such a manner that the main portion of the check is hidden from view, and which is arranged so as to operate positively and with little danger of getting out of order.

Reference is to be had to the accompanying drawings forming a part of this specification, in which similar reference characters indicate corresponding parts in all the views.

20 Figure 1 is a vertical section of the door check as applied to a door and frame, the door and frame being broken; Fig. 2 is a fragmentary plan view of the check and a portion of the door, Fig. 3 is a detail 25 inverted plan of the piston which forms a part of the check, and Fig. 4 is a detail sectional view on an enlarged scale showing the lower end of the valve plug.

The invention is provided with a casing 30 or well 10 which is preferably arranged in a vertical manner as hereinafter more particularly described, and this casing contains a vertically movable piston or plunger 11 which has a limited guided movement longitudinally of the casing, this movement being best regulated and guided by means of set screws 12, or equivalent abutments which extend inward from the casing wall and enter slots or key ways 13 in the outer wall 40 of the piston. The piston is hollow, and is cut off obliquely at the top as shown at 14, so as to give it a cam surface at its upper edge. The piston is normally pressed outward and upward by the spiral spring 15 which is arranged behind it. In the bottom of the piston is a hole 16 through which the oil or other liquid used in the check passes downward when the piston is raised, and this hole is closed at the bottom by a light 50 flat spring valve 17 which is fastened to the piston as shown at 18, and which has a small hole 19 through the center alining with the hole 20 in the bottom of the piston 11. The hole 20 is preferably screw threaded to receive the threaded lower end of the valve plug 21 which is notched at the top as shown

55 at 22 so that a screw-driver can be conveniently used to adjust the valve in the threaded hole 20. The valve plug 21 has a flattened bevel portion 21^a extending from the point to a little above the conical part of the plug, as shown in Fig. 4, so that by screwing the plug up or down, the flow of liquid can be regulated as more or less will pass, according to the position of the bevel portion 21^a in the bottom of the piston 11. This can be done by inserting a screw-driver through the hole 23 in the block 24 which is arranged at the top of the casing 10, and is fast to the spider 26, the latter being integral with the 70 cam 25 which is arranged within the casing 10 above the piston 11, the cam being hollow and having its lower edge cut obliquely but oppositely to the upper edge 14 of the piston 11.

75 It will be seen that when the cam 25 is rotated so as to bring the highest point of the cam opposite the highest part of the cam surface 14 of the piston, the piston will be depressed; but when the cam 25 is turned 80 so that its highest point moves away from the highest point of the piston, the latter will be permitted to rise under the impulse of the spring 15. A liquid such as glycerin, oil, or other suitable liquid, is used in the 85 check, and it will be observed that when the piston is raised, the oil will flow down through the hole 16, and the spring valve 17 is light enough to permit this action; but when the piston is forced down, the liquid 90 will flow up through the hole 19 in the valve and the hole 20 in the piston; this flow being regulated by the valve plug 21 which can be adjusted as above described.

95 The cam 25 is prevented from rising by a collar 26^a against which the spider 26 abuts, and the parts are all further held in place by a keeper-plate 27 which is fastened to the top of the door 34, hereinafter referred to, as shown at 28. The collar 26^a is fastened 100 to the top of the casing 10 by screws or otherwise, as shown at 26^b in Fig. 1. A block 24 is fast to the spider 26 and cam 25, and rotates in the keeper-plate 27, but the top of the block is squared as shown at 24^a in Fig. 105 2, and is connected with one arm 29 of a pair of arms which open and close like scissors, and which when the door is closed, lie flat over the top of the door. The second arm 30 of this pair is pivoted to the first arm 29 as 110 shown at 31, and is secured to the door frame 33 as shown clearly at 32 in Fig. 1. The

casing 10 is let into the top of the door and secured as shown and described.

When the door is opened, the arms 29 and 30 will open and gradually straighten out as indicated in Fig. 2, and the cam 25 will be turned so as to permit the piston 11 to rise under the impulse of the spring 15. As the door is opened and the piston 11 rises, the liquid will flow freely down through the hole 16 and against the light pressure of the flat spring 17; but when the door is closed by a spring or otherwise, the cam 25 is rotated so as to force down the piston 11 against the tension of the spring 15, and the liquid has to pass up through the holes 19 and 20 and over the flattened part 21^a of the valve plug 21, so that the amount of retardation will depend largely on the adjustment of the valve plug. It will be seen, therefore, that the amount of retardation can be nicely regulated, and it will be observed that there is very little about the apparatus to be seen and that the operation is positive and efficient.

25 I claim:—

1. The combination with a door and its frame, of a door check sunk in the top edge of the door, a pair of arms folding one over the other and adapted to lie parallel upon the door top, an operative connection between one of the arms and the door check,

whereby the swinging of the arm operates the check, and a connection between the second arm and the door frame.

2. The combination with a door and its frame, of a stationary casing sunk in the top end of the door, a piston having a guided longitudinal movement in the casing, means for holding the piston against rotation, means for retarding the downward movement of the piston, a rotatable cam held in the casing and acting against the piston to depress it, and a pair of folding arms pivoted together, one of said arms being operatively connected with the cam to rotate it, and the second arm being secured to the frame of the door.

3. The combination with a door and its frame, of a stationary casing sunk in the top edge of the door, a spring pressed piston held in the casing, valve mechanism to control the passage of liquid through the piston, a rotatable cam arranged in the casing above and acting against the piston, a projection on the cam, an arm secured to the projection and adapted to lie upon the door top, and a second arm pivoted to the first arm and also secured to the door frame.

CLARENCE T. ROGERS.
